UNITED STATES PATENT OFFICE.

BERT L. SHAVER, OF KANSAS CITY, MISSOURI.

PISTOL.

Application filed May 31, 1921. Serial No. 473,704.

To all whom it may concern:

Be it known that I, BERT L. SHAVER, a citizen of the United States, and resident of Kansas City, county of Jackson, State of Missouri, have invented a certain new and useful Improvement in Pistols, of which the following is a complete specification:

The present invention relates to fire arms, and aims to provide a simple and inexpensive fire arm construction having various novel and improved features not only in the firing mechanism but also in other parts of the construction.

Accordingly, one of the features of the improvement consists in a double hammer construction of such a character as to afford sufficient firing impact for percussion purposes, while at the same time eliminating any tendency to undue jar or shock to the gun or any objectionable recoil thereof. For this purpose I have provided a percussion hammer or block together with an impact hammer operating at the rear of the percussion hammer or block and adapted to fire the shell by a sharp blow delivered against the percussion block or hammer on release of the trigger. The construction provided is also such as to automatically lock both of the hammers in recoil position after each firing operation, for release of the shell and convenient reloading of the gun.

A novel form of hammer latching and releasing mechanism is also provided for accommodating the peculiar hammer arrangement, and allowing the impact hammer to be set and latched in either partly or fully cocked position.

Another feature of the improvement is a neat and conveniently operated form of hammer lock for the percussion block or hammer, which lock is also equipped with a spring element for holding it in either operative or inoperative position; in addition to which I also provide an improved spring-actuated ejector for extracting the shells when said hammer lock is in operative position.

For simplifying the construction, and reducing the cost of repair items, I have introduced the use of exterior springs for actuating the main hammer and attached such springs in exposed position in order that in the event of any defect or breaking of such springs they may be conveniently renewed or repaired, at a minimum of expense.

With these general objects in view, the

invention will now be described by reference to the accompanying drawings, illustrating one form of construction which I have devised for embodying the proposed improvements, after which the novel features therein will be particularly set forth and claimed:

In the drawings—

Figure 1 is a side elevation, showing a gun constructed in accordance with the present invention, with broken lines illustrating the safety-cock position of the rear or impact hammer;

Figure 2 is a plan view of the same; 70

Figure 3 is a central vertical sectional view of the gun;

Figure 4 is a side elevation, partly in section and showing the recoil position assumed by the hammers on firing of the gun; 75

Figure 5 is a transverse section taken on the line of V—V of Figure 4;

Figure 6 is a plan view of the gun with the barrel removed and hammer arms shown in section; and 80

Figures 7 and 8 are front views of the front and rear hammers, respectively.

Referring now to the drawings in detail, these illustrate the improved fire arm as comprising the usual stock portion 10 carrying a breech loading barrel 12 mounted in a suitable groove or channel 13 provided on the upper edge margin of the stock 10, and secured in place by means of a screw 14 extending upward through the forward end of the stock portion 10 and threaded into the bottom of the barrel 12, as clearly illustrated in Figure 3. For the firing of a shell 15 introduced within the breech end of the barrel 12 (as shown in Figures 3 and 4), I provide a percussion block or hammer 16 pivotally mounted opposite the breech of the barrel 12 by means of arms 19 engaging opposite sides of the stock 10 and pivotally connected thereto by means of a pin 17 passing transversely through the stock 10 and retained in position by means of a suitable screw 18 threaded into one end of the screw 17, as shown in Figure 5. The block or hammer 16 is formed with a suitable percussion rib or lug 16' for percussive engagement with the shell 15, as indicated in Figure 3. The hammer 16 is also held normally in forward position by the action of a coil spring 20 attached to a projection 21 depending between the arms 19, the other end of said spring being attached, as indicated

at 22, within a suitable longitudinal recess 23 formed in the upper portion of the stock 10.

At the rear of the hammer 16 is operatively mounted a second or impact hammer 25, which is somewhat heavier than the block or hammer 16, and similarly carried by means of arms 26 straddling the upper portion of the stock 10 and pivotally connected thereto by a pin 17 and screw 18, the same as with the hammer 16. This hammer 25 is adapted to be actuated forward into sharp engagement with the percussion hammer 16 by the action of a pair of coil springs 27, which are preferably mounted exteriorly and in exposed position by having their forward ends attached to hooks 28 projecting up from the top margin of the stock 10 at opposite sides of the barrel 12, and having the rear ends of said springs attached to hooks 29 formed on the opposite ends of a transverse element 30 extending through the hammer 25; the combined action of these springs 27 is also preferably greater than the action of the single coil spring 20 which is connected to the hammer 16.

The hammer 25 is adapted to be maintained in only partly cocked, or safety-cock, position as shown by the broken lines in Figure 1, or in full-cocked position, as shown by the broken lines in Figure 4, by engagement of a notch 32 formed on the hammer 25 with either of a pair of catch elements operating as hereinafter described. The means for retaining the hammer 25 in partly cocked position comprises a catch element 33 pivotally mounted upon a transverse pivot (as indicated at 34) within the longitudinal recess 23 (see Figures 3 and 4), the pivoted end of said catch 33 being provided with a depending finger portion 35 which is embraced between a coil spring 36 and a second catch element 37 mounted slidably within a drilled bore 38, the inner end portion of which bore forms a seat for said spring 36. The outer projecting end of the catch 37 is adapted for retaining engagement with the notch 32 of the hammer 25, while the inner end of the catch 37 is formed with a suitable notch 39 engaged by the upper end of a trigger element 40 pivoted upon a transverse pivot pin 41 within a recess 42 formed within the stock 10, as clearly shown in Figures 3 and 4. The usual type of trigger guard 43 is also provided for protecting the projecting portion of the trigger 40.

For convenience in ejecting the shell 15 when the forward hammer or block 16 is locked for firing, as hereinafter described, I provide an ejecting member 45 slidably mounted between the breech end of the barrel 12 and the upper margin of the stock 10, and formed with an upwardly projecting portion 46 countersunk within the breech

end of the barrel 12 and extending to the shell passage for appropriate engagement with the rim portion of the shell 15, as shown in Figures 3 to 5. An operating arm 47 is provided which is also slidably mounted between the stock 10 and barrel 12, and connected to the ejector element 45, as indicated at 48, this arm 47 being also formed with a lug portion 49 operating within a recess 50 in the stock 10 where a coil spring 51 is positioned for engagement with the lug 49, whereby the arm 47 and the ejector member are maintained normally in advance position with the ejector extension 46 seated against the breech end of the barrel 12. In the ejecting operation, therefore, it is only necessary to press against the free projecting end of the arm 47 to extract an exploded shell 15, as will be of course readily understood, the ejector then automatically returning to inoperative initial position. A slot 44 is formed in the arm 47 for engagement with the screw 17 and thereby limiting the ejecting movement.

I also provide a convenient means for locking the percussion hammer 16, when the gun is not in use, or for firing of more powerful shells, said means comprising a movable clip or detent element 55 mounted on top of the rear end of the barrel 12, with one end of the detent resting in a recess 56 and adapted to be reversed in position end for end with reference to the recess, so as to occupy either the inoperative position illustrated in Figures 3 and 4, or its operative position wherein the clip or detent is swung over the rear sight projection 57 as well as over the forward projection of the front hammer 16, and thereby preventing any backward movement of the latter. That portion of the clip which rests within the recess 56 is engaged yieldingly by a leaf spring element 58, against the action of which the clip or detent element 55 may be swung into either of its positions and obviously is yieldingly retained in such positions by said spring.

It is thus apparent that I have provided a comparatively simple and inexpensive, and yet thoroughly practical construction, for carrying out the desired objects of the invention. In explanation of the operation of the firing mechanism, comprising the hammers 16 and 25, and the catch and releasing mechanism therefor, it may be stated that normally, or when the gun is not in use, the forward block or hammer 16 is preferably engaged by the clip of detent element 55, as shown in Figures 1 and 2. At the same time the impact hammer 25 may be allowed to rest in engagement with the hammer 16, as shown in Figure 1, or it may be retracted into the dotted line position shown in Figure 1, representing the safety-cock position of said hammer 25, wherein it

is engaged by the catch 33 and may not be released from this position by pressure upon the trigger 40, on account of the contour of the notch 32 in said hammer 25. For firing purposes, when it is desired to operate the hammer block 16 as a movable hammer, the detent or clip 55 is swung forward out of engagement with the hammer 16 and into the position shown in Figures 3 and 4, and the impact hammer 25 brought back into fully cocked position in engagement with the catch 37, whereupon, by pressure upon the trigger 40, the catch 37 is retracted and the hammer 25 released to the action of its springs 27, which will result in a sharp blow being delivered upon the percussion hammer 16 and the firing of the shell 15. In this forward movement of the hammer 25, it will clear the free end of the catch 33, due to the latter being fully depressed by such movement of the catch 37 as is necessary to release the latter from its engagement with the hammer 25, as will be obvious on inspection of Figures 3 and 4. On explosion of the shell, the force of the recoil will result in simultaneous backward movement of both hammers 16 and 25, for some distance against the combined action of their springs 20 and 27, after which the action of said springs will cause a simultaneous return movement of the hammers, during which return movement the hammers will remain in engagement, on account of the relative greater strength of the pair of springs 27. In this movement, furthermore, the rear portion of the hammer 16 is maintained within what may be termed a notch 60 formed on the forward portion of the hammer 25, and after a certain extent of return movement of the hammers, the same will come to rest, due to the movement of the hammers about different centers as represented by the two different pins 17, so that the rear hammer 25 is in effect latched by means of the forward hammer 16, as shown in Figure 4, and retained so latched until the impact hammer 25 is released from engagement with the hammer 16 by backward pressure thereon and the percussion hammer 16 at the same time allowed to be returned to its forward position at the breech end of the barrel 12. This temporary holding of the hammers 16 and 25 in their recoil position is of advantage, since it allows the recharging of the gun with a fresh shell, without requiring any manipulation of the hammers, the fired shell having been automatically expelled by the force of the explosion. After the charging operation, the only further operation that is necessary before another firing of the gun is possible is the disengagement of the hammers 16 and 25 for restoring the hammer 16 to firing position and the hammer 25 to fully cocked position as represented by the broken lines in Figure 4. In the case of any extreme recoil on the part of the pistol, the shoulder 62 provided opposite the catch 37 would limit the recoil movement of the hammers, as will be obvious, but as ordinarily designed the recoil movement will not carry the hammers much past the position illustrated in Figure 4. By means of the double hammer construction arranged and operating as described, it is apparent that the weight of the movable or impact hammer may be reduced materially, and yet all the percussive force necessary be exerted without the attendant jar or shock usually experienced in the case of a heavier impact hammer, and by dividing the mass or weight between the two hammers, as shown, a sufficient weight is provided for keeping down the recoil movement to a more favorable minimum.

A further feature of improvement is seen in the automatic character of the shell ejector, which is self-acting in its return to original or inoperative position as shown in Figures 2 and 4. It will be understood that this ejector is used only where the lock 55 is employed in operative position for locking the hammer block 16 in firing position, as for longer rifle constructions, or for the firing of the more powerful shells, said hammer being unlocked after firing to permit operation of the ejector 45. Another improved feature (and which is of no small importance) is the construction which simplifies the repair of the gun in a case of defective parts, such as a broken spring 27 in which event these might be readily replaced, or any other suitable flexible spring element, such as a rubber band, be substituted for such springs at a trivial expense and without any such annoyance as would otherwise result from the gun being rendered inoperative. At the same time it will be noted that the other features of the pistol construction are of an extremely simple character and could be repaired by an unskilled novice and with very little time and labor. For example, the mounting of the hammers completely outside the stock portion of the gun, with their pivoted supporting arms arranged as shown, affords a structure which can not only be made more cheaply but is easy and economical to repair. The use of the contractile coil springs for pulling the hammers forward (instead of compression springs for exerting a pushing action at the rear of the hammers) is thought to be novel in this relation, and it is not intended, therefore, that the invention is to be confined to the mounting of the springs 27 at the exterior of the gun, as in some cases it may be preferred to mount them in enclosed position with their forward ends attached beneath the barrel, in the same manner as the coil spring 20.

The improved construction is also adapted to be modified so as to employ a single sufficiently light percussion hammer, adapted for the firing of smaller shells, such as BB cartridges, and which I therefore deem to be within the scope of my invention.

Another feature of advantage in connection with the action of the hammer or block 16 and the retention of this hammer in its recoil position after firing, is the fact that it is not allowed to be driven forward against the breech end of the barrel after the shell has been blown out, and thus the improved construction serves to prevent the 10 battering and marring of these parts because the hammer or block 16 is never in its forward position except when a shell is in position for firing.

While I have illustrated and described 20 what I now regard as the preferred form of construction for embodying the proposed improvements, I desire to reserve the right to make such changes as may fairly fall within the scope of the following claims.

25 What I claim is:—

1. A pistol construction comprising a breech-loading barrel, a percussion hammer pivotally mounted in operative relation to the breech end of said barrel, and an impact 30 hammer operatively mounted at the rear of said first said hammer and independent of the latter.

2. A pistol construction comprising a breech-loading barrel, a percussion hammer 35 mounted in operative relation to the breech end of said barrel, and an impact hammer movably mounted at the rear of said first hammer, said hammers being movable rearwardly into recoil position after each firing 40 operation and provided with coacting means for retaining said hammers in recoil position.

3. A pistol construction comprising a breech-loading barrel, a percussion hammer 45 pivotally mounted at the breech end of said barrel, and an impact hammer mounted for independent movement at the rear of said first hammer, said hammers being movable rearwardly into recoil position after each 50 firing operation and provided with coacting means for retaining said hammers in recoil position.

4. A pistol construction comprising a breech-loading barrel, a percussion hammer 55 and an impact hammer mounted for independent pivotal movement about separate axes at the breech end of said barrel, said percussion hammer being operative to latch

said impact hammer in recoil position after the firing operation.

5. A pistol construction comprising a breech-loading barrel, a percussion hammer pivotally mounted at the breech end of said barrel, and an impact hammer mounted for independent movement at the rear of said first hammer, a spring acting to maintain said percussion hammer normally in forward position, and relatively stronger spring means for actuating said impact hammer, said percussion hammer being operative to latch said impact hammer in recoil position after each firing operation.

6. In a pistol construction, a hammer movable into either partly cocked or fully cocked position, a spring-actuated catch element for retaining said hammer in partly cocked position, and a second spring-actuated catch element for retaining the hammer in fully cocked position, said first catch element being adapted for movement independent of the second catch element for effecting retaining engagement with said hammer.

7. In a pistol construction, a hammer movable into either partly cocked or fully cocked position, a catch element for retaining said hammer in partly cocked position, a second catch element for retaining the hammer in fully cocked position, said first catch element being adapted for movement independent of the second catch element for effecting retaining engagement with said hammer, and a trigger arranged to actuate both of said catch elements for releasing the hammer.

8. In a pistol construction, a hammer movable into either partly cocked or fully cocked position, a catch element for retaining said hammer in fully cocked position, a trigger for actuating said catch element to release the hammer, and a second catch element for retaining said hammer in partly cocked position and adapted to be moved by said trigger to entirely clear said hammer as the latter is released from fully cocked position.

9. A gun construction comprising a stock, a breech-loading barrel thereon, and a trigger-operated catch comprising a pin slidingly mounted in said stock and having its rear end adapted to be projected outwardly from the rear portion of said stock into position for detachable engagement with said hammer.

In witness whereof I hereunto affix my signature.

BERT L. SHAVER.
